(57) CLAIM

The ornamental design for a display screen or portion thereof with animated icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a first image in a sequence for a display screen or portion thereof with animated icon showing my new design;

FIG. 2 is a second image thereof;

FIG. 3 is a third image thereof;

FIG. 4 is a fourth image thereof; and,

FIG. 5 is a fifth image thereof.

The broken lines illustrating portions of the display screen or portion thereof with animated icon are for environmental purposes only and form no part of the claimed design.

The broken-line outline of a circle shown with a short-and-long dash pattern in FIGS. 1-5 illustrates the bounds of the icon and forms no part of the claimed design.

The appearance of the image transitions sequentially between the images shown in FIGS. 1-5. The process or period in which one image transitions to another forms no part of the claimed design.
